The ornamental design for a washing and curing machine, as shown and described.

DESCRIPTION

FIG. 1 is a perspective view of a washing and curing machine showing my new design according to a first embodiment;

FIG. 2 is a front view thereof;

FIG. 3 is a rear view thereof;

FIG. 4 is a right side view thereof;

FIG. 5 is a left side view thereof;

FIG. 6 is a top plan view thereof;

FIG. 7 is a bottom plan view thereof;

FIG. 8 is a perspective view of the washing and curing machine in an alternate condition of use when a transparent cover is open; and,

FIG. 9 is a perspective view of the washing and curing machine in an alternate condition of use when a bucket for washing is taken down and a platform for curing is coupled. The broken lines are for the purposes of illustrating portions of the washing and curing machine and form no part of the claimed design.
